UNITED STATES PATENT OFFICE.

GEORGE REGINALD HUDSON, OF LONDON, ENGLAND.

PROPELLER PENCIL.

Application filed February 2, 1922. Serial No. 533,616.

To all whom it may concern:

Be it known that I, GEORGE REGINALD HUDSON, of 612, Bank Chambers, High Holborn, London, W. C. 1, England, a subject 5 of the King of Great Britain and Ireland, have invented certain new and useful Improvements in or Relating to Propeller Pencils, of which the following is a specification.

This invention relates to propeller pencils 10 of the type in which the lead is held in a carrier provided with a key adapted to travel in a slot in a tubular member in which the carrier moves, the key being provided with a notch adapted to engage a wire coil 15 wound in the form of helix around the tubular member.

In pencils of this type as hitherto constructed the helical member is enclosed in and soldered to a holder or coil box and the 20 tubular member is placed in and secured to a casing so that when rotating the holder with respect to the casing, the helical member is rotated causing the carrier to move along inside the slotted tubular member.

25 In such known pencils damage may be caused to the mechanism by overwinding and causing the spring or coil to become detached from the holder or coil box, and further there is generally a little back lash 30 or movement between the holder and the slotted tubular member.

The object of this invention is to overcome these defects.

In a pencil made in accordance with 35 this invention the helical member is in frictional contact with the holder or coil box and is formed or bent to provide a stop to engage the key at the end of its forward or backward movement so that in use should 40 an attempt be made to overwind the pencil there is no soldered joint which can come undone, but the holder or coil box merely slips on the spring without any undue turning pressure. In order to take up back lash 45 a compression spring is inserted between a flange on the holder or coil box and a flange on the slotted tubular member.

In the drawings filed herewith:

50 Fig. 1 is a partly sectional view of one form of pencil made in accordance with this invention in which the wire helix is shown in full;

Fig. 2 is an elevation of the lead carrier;

Fig. 3 is an end view of the carrier;

55 Fig. 4 is a sectional elevation of a modi-

fied form of pencil made in accordance with this invention.

Fig. 5 is a fragmentary sectional view illustrating a further modification.

Referring to the drawings:

a is the carrier provided with a key b in which a notch b' is provided and c is the lead. The carrier is adapted to travel in a tubular member d, the key b passing along the slot e formed in the member d and shown in the drawings in dot and dash lines. Round the tubular member d a wire f is wound in the form of a helix the wire engaging the notch b' in the key b. The ends of the wire are bent at g and h so 70 as to lie parallel to the longitudinal axis of the pencil and form a stop to engage the key b when the carrier is at either end of its movement. Over the helical member f is a holder j, provided with an internal collar or flange k. The end of the holder is provided with a chamber m and cap n to hold the spare leads as is common with propeller pencils. The open end of the tubular member d is provided with a casing 75 or front part o fixed to it.

In Fig. 1 the end of the tubular member d is shown expanded over a washer placed against the flange k.

In use to propel the lead the holder j is 80 rotated with respect to the tube d and casing o. The helical member f is carried round with the holder by frictional engagement therewith and the key b engages the helical member causing the carrier a to travel in the tubular member d until the carrier comes to the end of its movement when the key b engages the end g or the end h of the helical member. Should an attempt be made to overwind the pencil the 85 holder slips on the helical member and no damage is done to the moving parts.

In Fig. 4 the back part of the flange k is cut away to allow a small compression spring p to be inserted between the said flange k and the washer q as shown. This modification does not make any appreciable difference in the strength of the flange k which still retains a considerable thickness.

The effect of the compression spring p 100 inserted in the manner indicated is to hold the casing or front part o of the tubular member d firmly against the front end of the holder j, to take up wear, and to compensate for any other causes tending to pro-

duce backlash between the two parts referred to.

In the form of pencil illustrated in Fig. 5 the inside of the holder *j* is provided with 5 a brass tubular lining *r* which has at the front end a flared or enlarged conical portion *s* which is adapted to engage a groove *t* in the holder *j*. Near the other end of the lining *r* and in a position corresponding 10 to that of the flange *k* in the pencil-holders hereinbefore described, is an internal ridge *u*, while a brass bushing *v* having a peripheral groove corresponding to the ridge *u* is adapted to be secured in the 15 tubular lining *r* to take the place of the flange *k* in the pencil-holders already described. Thus the components *j*, *r*, and *v* form a compound integral structure constituting the holder proper denoted by the 20 letter *j* in the other examples. The tubular member *d* passes through a hole in the bushing *v* and is flared and provided with a washer *q* and preferably, a compression spring *p* as already described. This form 25 is particularly efficient in that, owing to the manner in which the holder *j*, tubular lining *r* and brass bushing *v* are secured together, it is impossible to pull the pencil-holder to pieces as in the case of so many propelling pencil-holders now constructed; and the provision of the brass lining *r* prevents the holder *j* from warping when of a 30 material liable to warp and rendering the pencil-holder useless.

35 What I claim and desire to secure by Letters Patent is:—

1. In a pencil, the combination with a 40 rotatable holder, of a rotatable helix within the holder for extruding and withdrawing the movable pencil point, the turns of said helix being expanded into frictional engagement with the interior of the holder

so as to rotate with the rotation of the holder, said holder being adapted to slip upon the helix in case the further rotation 45 of the helix is obstructed.

2. In a propeller pencil, the combination with a carrier for the lead, of a tubular member surrounding the carrier, a slot in the said member, a key on the carrier projecting into the slot, an opening in the key, a wire helix surrounding the tubular member engaging in the said opening, the ends of the helix being bent into a position parallel to the longitudinal axis of the pencil to form steps to engage the said key at each end of the movement of the carrier, a holder enclosing the tubular member and making frictional engagement with the helix, and means for retaining the tubular member stationary while rotating the holder and helix to extrude and withdraw the lead as desired.

3. In a propeller pencil, in combination, a carrier for the lead, a tubular member 65 surrounding the carrier, a slot in the said member, a key on the carrier projecting into the slot, an opening in the key, a wire helix surrounding the tubular member engaging in the said opening, a casing fixed 70 to the front part of the tubular member, a holder making frictional engagement with the helix enclosing the tubular member and abutting against the said casing, an internal shoulder near the rear end of the holder, a collar on the rear end of the tubular member, and a compression spring inserted between the said shoulder and the 75 washer to maintain the rubbing contact between the front end of the holder and the casing fixed to the tubular member.

In testimony whereof I have signed my name to this specification.

GEORGE REGINALD HUDSON.
